CLAIM

The ornamental design for a hood latch for a vehicle, as shown and described.

DESCRIPTION

FIG. 1 is a rear perspective view of a hood latch for a vehicle showing our new design;

FIG. 2 is a front perspective view thereof;

FIG. 3 is a side elevational view thereof;

FIG. 4 is an opposite side elevational view thereof;

FIG. 5 is a front elevational view thereof;

FIG. 6 is a rear elevational view thereof;

FIG. 7 is a top plan view thereof; and,

FIG. 8 is a bottom plan view thereof.

It will be understood that the broken lines shown in the drawings illustrate portions of the hood latch for a vehicle that form no part of claimed design.

1 Claim, 7 Drawing Sheets
